UNITED STATES PATENT OFFICE.

JOHN L. LEWIS, OF PITTSBURG, PENNSYLVANIA.

METHOD OF TREATING HOT-ROLLED BARS WHILE COOLING.

SPECIFICATION forming part of Letters Patent No. 278,246, dated May 22, 1883.

Application filed September 19, 1882. (No model.)

To all whom it may concern:

Be it known that I, JOHN L. LEWIS, of Pittsburgh, in the county of Allegheny and State of Pennsylvania, have invented certain new and useful Improvements in Methods of Cooling Metal Bars After Rolling; and I do hereby declare that the following is a full, clear, and exact description of the invention, which will enable others skilled in the art to which it applies to make and use the same, reference being had to the accompanying drawings, which form a part of this specification, in which—

Figure 1 is an end view of one form of my apparatus. Figs. 2 and 3 are similar views of modifications.

In the manufacture, by rolling, of iron and steel rods, shafts, bars, &c., as at present universally practiced, the finished product of the rolls is drawn off to what is usually termed the "cooling-bed." This may be the ground or iron plates known as the "standing," which are laid over a considerable space near to the rolls, or are laid upon rails or bars supported in parallelism at intervals, and there allowed to cool. In any case the rod or bar, coming at usually a red heat, from the rolls, lies inert upon the cooling-bed until cool. The result is that the under side becomes cooled more rapidly than the upper side, which latter has only the atmosphere to cool it, while the former has the assistance of the direct conduction obtained from contact with the cooling-bed. This effects a warping of the bar, causing it to assume a very irregular form longitudinally, which necessitates considerable labor afterward in order to straighten the bar. This warping of the bar occurs chiefly during the lowering of the temperature from a red to a "twilight" heat. It is a great drawback to the subsequent manipulation of the bar, whether it be a round for shafting or rod, a square, oval, or other regular form, wherein the warping is not due to the preponderance of metal in any one part of the section.

The object of the present invention is to prevent this warping of the rolled article, so that when cool it shall be as straight as is compatible with the ordinary process of rolling, as now practiced in rolling-mills generally.

To this end my invention consists in taking two or more bars or other product from the

rolls, and, while cooling, subjecting them to and maintaining them in motion while in mutual contact until cooled to such an extent as to be unaffected by the slight additional cooling thereafter occurring, substantially as herein-after described and claimed. The method may be practiced in a number of ways without departing from the essence of the invention. For instance, I can adopt the means illustrated in Fig. 1. In this, A designates the cooling-bed, consisting of a number of horizontal parallel plates or rails. In a pit under the cooling-bed A, I place a steam-cylinder B, having piston-rod, C, extending outwardly and attached to the frame or bracket D, which is set on slides E in the pit. From bracket D extend upwardly two standards or arms, F, which project somewhat above the level of the cooling-bed, as shown, as the injurious warping takes place only before the bars have cooled to a black or twilight heat, and as the bars are usually rolled in quick succession, I roll several bars, a a, and lay them across the cooling-bed A, and then admit steam to cylinder B and start its piston in motion. This produces a reciprocation of the frame D and the arms F, and the bars a are thereby caused to roll slowly back and forth over the cooling-bed A. Consequently the bars a are constantly in motion and as constantly change the surface in contact with the cooling-bed and each other. Hence the bars cool off uniformly, and the cooling of any one side cannot take place in advance of the remaining surface of the bar, and therefore the bar, when cool, will not be warped, but practically straight and true. Another means is shown by Fig. 2, where the piston-rod G of cylinder H is connected by rod I to a crank, K, on a rock-shaft, L. Crank K extends upwardly into contact with the cooling-bed, consisting of several parallel rails, M, having upturned ends. Bed M, at the side opposite the crank K, is journaled on the shaft or pivot N, so as to be capable of oscillating or rocking. The rolled bars a are laid on bed M, and the motion of the piston causes the crank K to rock and alternately lift and lower that side of bed M above and below a horizontal line, causing the bars a to roll back and forth on the cooling-bed in mutual contact. Another form is shown by Fig. 3, where P are

the rails of the cooling-bed, inclined as shown. R is a standard, through whose base is fitted the screw S. On end of screw S is a spring ratchet or crab, T, operated by a spring treadle, V. When the workman places a bar, a, on the bed P he depresses treadle V with his foot. This rotates screw S and moves standard R backward slightly, thus allowing all bars a on the bed to roll slightly downward in mutual contact, and thus at intervals sufficiently rapid, the bars' positions are changed and the unequal warping prevented, as before. In all these cases the bars may be piled as in Figs. 1 and 2. When the bars are cooled to such extent as to be in no danger of warping by the subsequent contact with the ground they may be removed from the cooling-bed to another part of the mill.

I am aware that it has been proposed to revolve rolled bars singly on overlapping rollers and pour water on them while in motion; but my invention aims at the cooling of bars in mutual contact and without the use of water, whereby I am enabled not only to pile a great number of bars together on the cooling-bed, but also to effect the cooling of both iron and steel bars or rods.

While I have shown specific devices for carrying out my invention, I do not herein lay claim to any mechanism, as I propose to make such the subject of one or more separate applications. They are used herein merely for illustration.

I am also aware that it has been proposed to give the rolled bars a transverse rolling or

reciprocating oscillatory movement by laying them on a suitable bed capable of giving such motion, and separating the bars from one another by means of uprights or pegs. I do not claim such a method of cooling. As before stated, one of my principal objects is to cool a large number of bars in as little space as possible, which requires the bars to be placed in mutual contact, which in turn insures an equitable and uniform cooling without warping or irregular contraction.

I claim as my invention—

1. The method of treating rolled metal bars during the process of cooling, consisting in placing two or more bars in mutual contact and imparting to said bars a rolling or oscillating movement, whereby the points or lines of mutual contact undergo change and uniform cooling is effected, substantially as described.

2. The method of treating rolled metal bars during the process of cooling, consisting in placing two or more bars in mutual contact on a suitable bed, then imparting to said bars a rolling or oscillating movement, and thus successively changing the points of contact of said bars with each other and with the bed.

In testimony that I claim the foregoing as my own I have hereto affixed my signature in presence of two witnesses.

JOHN L. LEWIS.
